US00D802527S

(12) **United States Design Patent** (10) Patent No.: **US D802,527 S**
Cardoso et al. (45) Date of Patent: ** Nov. 14, 2017

(54) **STRUCTURAL SUPPORT FOR SOLAR ENVELOPE AND SOLAR COLLECTOR**

(71) Applicant: **ALVA ALTA**, Lisbon (PT)

(72) Inventors: **Paulo A. Cardoso**, Lisbon (PT); **Daniel Caramelo**, Lisbon (PT)

(73) Assignee: **ALVA ALTA**, Lisbon (PT)

(**) Term: **15 Years**

(21) Appl. No.: **29/575,987**

(22) Filed: **Aug. 30, 2016**

Related U.S. Application Data

(62) Division of application No. 29/528,200, filed on May 27, 2015, now Pat. No. Des. 768,282.

(57) **CLAIM**

The ornamental design for the structural support for solar envelope and solar collector, as shown and described.

DESCRIPTION

FIG. 1 is an elevated, perspective view of the structural support for solar envelope and solar collector showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
